LOCK FOR KNIFE SWITCHES

Lawrence H. Russell, Saginaw, Mich.

Application May 15, 1942, Serial No. 443,039

3 Claims. (Cl. 200—44)

This invention relates to a new and useful retainer or lock for knife-switches, particularly that type of switch having two or more spaced parallel blades connected by a cross-bar of insulated or insulating material. It has for its object the provision of simple, inexpensive, and positive means which, in various modifications, may be used with any conventional switch of this kind to prevent hasty, accidental, or unauthorized movement of the switch in either direction, whereas previous locking or latching devices have operated only to hold a switch closed. In other words, my improved lock operates to prevent closing an open switch or opening a closed switch, as the case may be.

A further object is to provide a lock which can be applied to existing switches without any modification of the switch structure, whereas previous locking or latching mechanisms have been built into the switches.

The invention makes possible the use of a simple, inexpensive device which, manufactured in a few sizes, can be employed to lock or latch any standard knife-switch already installed, without the necessity of altering the switch or disturbing its installation.

Another advantage of the device of the invention is that, being entirely separate from the conductive elements of the switch, and designed for installation on the insulated switch panel so that it at no time can come in contact with any conducting member, it minimizes hazards and renders unnecessary the use of a hot stick or other insulated tool to actuate it.

Other features and advantages of my invention will be apparent in the course of the following specification.

Referring to the accompanying drawing, Fig. 1 is a side elevation, partly in section, showing a device according to the invention applied to a knife-switch of standard form;

Fig. 2 is an enlarged part-sectional side elevation of the lock and switch of Fig. 1, showing it equipped for key control; and

Fig. 3 is a side elevation of a modified form of lock according to the invention.

Referring to Fig. 1, a knife-switch having two or more parallel blades A connected by a cross-bar B of ebonite, or other insulating or insulated material, is mounted on a switch panel C.

The improved lock shown in Figs. 1 and 2 consists of a body member 1 presenting an abutment head 2, pivoted on a pintle 3 carried by a base member 4 which is secured to the panel C. Member 1 has an integral foot or stop member 5, ex-

tending upward in the drawing, which by engaging base 4 limits the upward or counter-clockwise movement of member 1 on its pintle. Below the pintle, member 1 presents an abutment face 6 at an angle to the face of foot 5 which similarly limits the downward movement of member 1, clockwise in Figs. 1 and 2. The abutment head or stop member 2 is spaced from the foot to provide a relief to accommodate the switch cross-bar B.

The base plate 4 is located upon the panel C so that the body 1 or head 2 can not touch any blade A of the switch, and the abutment head 2 when lowered clears the path of movement of the cross-bar B. When the body member 1 is raised to its uppermost position the head 2 lies in the arc of movement of the cross-bar B. If the switch is closed, as shown in solid lines, the inner face of the head 2 lies over the cross-bar B to prevent opening the switch. When the switch is open, as indicated in broken lines, the outer face of head 2 obstructs the cross-bar B so that the switch can not be closed.

Various quick-acting devices may be utilized to actuate or retain the pivoted body member 1 and abutment head 2 in locking position. For example, Fig. 2 shows a bore 7 lengthwise through the body 1 receiving a pin 8 which is movable to take against the base plate 4 and hold the member 1 up in locking position. The bore 7 is tapped for a short distance and pin 8 is threaded at 9 so that a few turns of the pin by its knurled head 10 will lock member 1 in its raised position.

Intermediate its ends pin 8 may be relieved or reduced in diameter as at 11. A set screw 12 is inserted through the wall of member 1 with its end received in the relieved portion 11 so that when the threads of the pin are disengaged from the threads in bore 7 vibration can not cause the bolt to drop out.

The device of Fig. 1, when raised, prevents accidental opening or closing of the switch, and also discourages its mistaken operation by an excited operator because of the time interval required to turn pin 8 and release the switch.

When it is desired to prevent unauthorized, as well as accidental or erroneous operation of a switch, the pin 8 may be provided with a key-actuated mechanism 13 indicated in Fig. 2, which operates to withdraw catches 14 from an annular recess in the wall of bore 7.

Fig. 3 shows a modification of the locking device of Figs. 1 and 2, adapted to be installed so that it normally hangs in switch-locking position. The body member 1 and the abutment head 2 are

formed for installation above the cross-bar B of the switch, being pivoted to pintle 3 on base 4a. The movement of body member 1 about pintle 3 is limited by a latching stop member 8a. In the example shown, the latching action is provided by splitting the inner end of the movable pin 8a by intersecting slots 17 so that it is compressible diametrically. The inner end of the pin 8a is upset to provide a shoulder 15 of larger diameter than the body of the pivot. The enlarged end has its corner beveled for latching engagement in a shouldered recess 16 in the base plate 4. The outer edge of the shouldered recess is also beveled so that when the locking member is allowed to drop down with normal force the split shoulder 15 will be compressed and catch within the aperture 16.

To release the catch, the split end portion of pin 8a is reduced in diameter to present a tapered portion 19 just beyond the end of the bore 7 in the body member. Drawing the pin 8a outwardly or urging the body member 1 inwardly relative to the pin compresses the split end of the pin so that the shoulder 15 at its extremity will pass through the restricted portion of aperture 16 in the base plate 4a.

For automatic latch action the pin may be normally urged to the right in Fig. 3 by spring means not shown. Or, as shown, the body of the pin may be grooved at 21 lengthwise, then transversely. A set screw 20 in the wall of member 1 extends into groove 21 so that the pin may either be locked in place, or when turned slightly by its knurled head 18 will be movable endwise. When it is fixed endwise the latching action is automatic and the latch can be disengaged only by turning the pin until the set screw 20 is in the longitudinal part of groove 21.

If desired, a key control as shown in Fig. 2 may be employed with the pin 8a.

The automatic latching device of Fig. 3 will be found particularly useful in installations where quick opening of the switch is desirable. The chances of accidental or hasty opening or closing are minimized, as the operator must use both hands to open or close the switch.

In some instances a fixed abutment may take the place of the latching pin 8a. The abutment head 2 prevents accidental opening of the switch since it normally hangs in the position

shown, and to open or close the switch the operator must lift and hold the latching device out of the way of the cross-bar B with one hand in order to open or close the switch.

It is to be understood that the forms of my invention herewith shown and described are to be taken as preferred examples of the same, and that various changes in the shape, size, and arrangement of parts may be resorted to without departing from the spirit of the invention or the scope of the appended claims.

Having thus described my invention, what I claim and desire to secure by Letters Patent is:

1. A locking device for a knife-switch having a cross bar comprising an abutment member movable into and out of the path of travel of said cross bar effective when in said path of travel either to prevent closing the open switch or to retain the switch closed, said abutment member being pivoted to a base plate adapted to be fastened to the panel, and means for positively retaining said abutment member in the path of said cross bar, said retaining means comprising an adjustable stop provided on said abutment member to bear against said base plate.

2. A locking device for a knife-switch having a cross bar comprising an abutment member movable into and out of the path of travel of said cross bar effective when in said path of travel either to prevent closing the open switch, or to retain the switch closed, said abutment member being pivoted on a pintle carried by a pad adapted to be fastened to the switch panel, and quick acting screw means provided on said abutment member adapted to bear against said pad and retain the abutment member in locking position.

3. A locking member for a knife switch comprising in combination a body member having an abutment head and pivoted on a base member which is adapted to be secured to the support of the knife switch, said abutment head formed with a stop member adapted to engage said base to limit the pivotal movement of the abutment head in one direction, said body member being also provided with quick acting retaining devices comprising a pin movable lengthwise of the body member and threaded thereto, and key-actuated locking means for securing said pin in said body.

LAWRENCE H. RUSSELL.
